CARBON DIOXIDE ICE COOLING SYSTEM

Harry S. Cornish, Los Angeles, Calif.

Application May 14, 1930, Serial No. 452,243

12 Claims. (Cl. 62—91.5)

My invention relates to cooling apparatus in which solid carbon dioxide or other gas reduced to ice is employed as a refrigerant and more particularly to a form of apparatus wherein the released gas assists in cooling the contents of the cooler.

The invention will be described as carried out by the utilizing of carbon dioxide ice as the solidified refrigerant adapted when it absorbs heat from the contents of the cooler to release or evolve the gas although it is capable of use with other gaseous agents transformed into ice by any suitable means.

One of the objects of my invention is to so construct the apparatus that gas may be accumulated and retained under pressure within the cooler so as to be itself utilizable as a gaseous agent under positive pressure for carbonating or similar treatment of liquids.

The invention consists in a cooler having means for supporting from its top a steel tank or drum of the usual form adapted to withstand heavy pressure when loaded with carbon dioxide ice and projecting inwardly or downwardly from said top into the cooler so as to absorb heat from the contents of the cooler and providing the tank with an outlet connected to piping for delivering the evolved carbon dioxide gas into the cooler through a valve which preferably is controlled from the outside of the cooler by suitable manual or other devices said cooler receiving the outflow from said valve controlled pipe and being constructed with a gas-holding chamber or gas-holding portion of the chamber in such manner that it shall be capable of withstanding considerable gas pressure without leakage whereby in the case of carbon dioxide the accumulated gas may be employed directly if desired as a carbonating gas for carbonating liquids.

Another object of my invention is to facilitate the re-loading of the cooler with the cooling gas-producing ice and to this end my invention consists in mounting a carbon dioxide ice steel tank or drum in the top of the cooler in position to project downwardly into the cooler chamber said drum being provided with a removable cap or head located outside the cooler to permit ready reloading without disturbing the connections for conducting the evolved gas into the cooling device located in said cooler all as will be more particularly hereinafter described.

The invention further consists in constructing the cooler with means for supporting a multiplicity of the ice containers and combining therewith a suitable gas valve or valves whereby the same may be at will connected with the gas spaces of the cooler thereby permitting the loading of the cooler with ice sufficient for prolonged use of the cooler without re-loading with ice.

The invention also relates to a construction

wherein the ice containing tank or tanks are provided with gas outlet pipes leading downward into the cooler space and equipped with a suitable controlling valve or valves one of which is provided with a stem extending through a side wall of the cooler for manual or other operation as desired to control the flow of the cooling dioxide gas into the space or spaces below the steel drum or drums for passage through gas circulating conduits of a heat transfer and eventually out through a side wall of the cooler all as will be hereinafter more particularly described and claimed.

My invention further consists in the constructions of apparatus and combinations of devices facilitating the use of CO₂ ice and the gas evolved therefrom as the cooling agent as hereinafter more particularly described and then specified in the claims.

Referring to the accompanying drawings:

Fig. 1 is a vertical section of a typical form of apparatus embodying the invention, CO₂ ice container or containers being shown in elevation with their contents of CO₂ ice illustrated in dotted lines as rectangular blocks of ice.

Fig. 2 is a cross-section through Fig. 1 on the line 2—2.

Fig. 3 is a view similar to Fig. 1 and illustrates the invention in modified form.

Fig. 4 is a horizontal cross-section on line 4—4 of Fig. 3.

Fig. 5 shows another form of the invention wherein the pressure-proof ice container is in direct contact with the part of the liquid to be cooled.

Fig. 6 is a horizontal cross-section on the line 6—6 of Fig. 5.

Fig. 7 is a vertical section showing a modification in the construction of the ice container drums.

Fig. 8 is a similar section of a further modification.

Fig. 9 illustrates a modification or variation in the application of my invention.

In Fig. 1 the body of the outer shell or casing of the gas pressure-proof container and cooler is indicated at 1. A removable cover plate 1' is properly applied and secured upon the body 1 to afford a gas pressure-proof joint thereby sealing the spaces within the container against escape of the gas confined therein under considerable pressure, said pressure being preferably sufficient to permit the use of the gas directly in carbonating a liquid or for other purposes requiring positive gas pressure without the intervention of any means for raising the pressure in the carbonator. The cover and body are preferably made of some heat-insulating substance or if made of metal are provided with heat-insulating linings or jackets. For convenience the cover plate 1' being made removable is held in place by suitable clamping

devices 2 which hold the cover 1' down upon the edge of the shell or body 1, a suitable gas sealing gasket being interposed preferably as indicated at 3. Metal containers, drums or holders 4 for the CO₂ ice are mounted or applied to project into or be located entirely within the gas containing and retaining space of the cooler and so as to acquire heat from the contents in the container which are to be cooled. Said ice containers 4 consisting of heavy steel tanks or drums of the form frequently employed to handle liquid carbon dioxide and to withstand the heavy pressures of the contents, either of liquid or gas, when they are loaded. They are as usual hermetically sealed but have outlet pipes 7 for any gas evolved from the CO₂ ice within the same and allowed to escape, said pipes being connected with the downwardly extending passage or pipe 5 as shown and being each provided also if desired with means for controlling the flow from it to the pipe 5. By these means the high pressure gas developed or released by the effects of heat on the ice contents of the ice container 4 may be conducted to the interior gas-retaining and holding spaces of the cooler. Each container is adapted to receive a block of CO₂ ice or similar ice that in dissipating will release CO₂ gas or similar gas.

These drums or cartridges are of heavy metal capable of withstanding high internal pressures and may be similar to those heretofore used for transporting carbon dioxide under heavy pressure for use in connection with carbonators for soda fountains. For the use of my present invention however the drum is preferably suitably modified in construction to permit it to be loaded with a block of carbon dioxide ice introduced into the same as described through a removable head. To enable this to be done and without disturbing the gas connections from the drums I provide removable gas tight heads or sealing caps 9 for the drums located outside the top of the cooler or portion thereof in which the drums are mounted. To reload with the CO₂ ice the cap 9 is removed and the ice inserted in suitable amount according to the pressure of evolved gas desired. The cap 9 is then reapplied to seal the drum gas tight. The block of ice is indicated at 6 in dotted lines and is of a size limited to permit or provide a considerable space within the ice drum which shall be free and allow accumulation of the gas under pressure therein. In the form shown the gas spaces of the containers may be joined through the pipes 7 in a valve casing 8 which is provided with a suitable valve similar to a three-way valve whereby, when a number of ice containers 4 are used, said containers may be placed in communication at will with pipe 5 and the interior of the cooler or shut off from connection therewith.

Other forms of high pressure steel tank or drum mounted in the head of the cooler and having suitable provision to permit the drum to be reloaded from the outside and to be secured gas tight after reloading might be employed in the place of those shown, suitable provision being made in connection with the same for leading the gas evolved in the tank through a pipe or pipes into the cooling space of the cooler, the drum being, however, located so that the major portion thereof will be exposed to or affected by the temperatures prevailing in the cooler and so as to readily absorb heat from the interior of the cooler and cause the dry ice to evolve the CO₂ gas.

When a battery or gang of ice containers 4 is provided the valve 8 permits them to be put

into service one after the other as they become exhausted, the one or more ready for service being preferably cut off at such time. While one or more are in service the remainder are retained or held in reserve or ready for use as occasion may require. Any form of the movable cap 9 adapted to be screwed down upon the end of the drum or otherwise secured in gas-tight relation to the body might be employed for reloading purposes if adapted to prevent escape of the high pressure gas excepting through the pipe connections 7 and valve 8 to pipe 5 and thence to the interior of the cooler. A suitable projecting valve stem 12 is provided to permit manipulation of the valve 8 from the outside. The drums or holders 4 fit tightly as possible in the openings in the cover 1' through which they pass so as to prevent leakage of gas from the spaces of the cooler into which the gas passes from the holders or drums 4. A supplemental cover plate 20 (not shown) and enclosing the heads of the ice drums 4 may be also provided and secured to the cover 1' by suitable clamps which fasten the same down firmly intermediate gas-tight gaskets being provided. By this means escape of gas which may leak around the sides of the metal ice containers 4 at the point where they pass through the head or cover 1' or around other projecting parts may be prevented. By removing the supplemental cover access to the ice containers for introduction of a fresh supply of ice is obtained.

It will be understood that valve stem 12 should have a suitable gas-tight packing or gasket at the point where it passes through the cover 1'. It is obvious that any desired number of ice drums may be employed within limits. The drawings show four in number but it would be within my invention to employ but one. Pressure gages 31 may be connected to the containers 40 to show when they are empty or when the pressure falls so low as to demand the operation of valve 8 to shut off a container and to place a new one in connection with pipe 5 and the interior of the cooler.

In the form of the invention illustrated in Fig. 1 the device is shown as applied to the cooling of a liquid. Said liquid may be circulated through liquid-containing spaces in the lower portion of the chamber 1 where a liquid holder or container, itself preferably made of metal, is exposed to the cooling effects of the ice and of the CO₂ gas escaping from the lower end of pipe 5 and circulated through suitable gas tubes or passages of a heat transfer device having water circulating passages the walls of which constitute a wall of the gas circulating passage. Before entering the gas passages for the CO₂ gas said gas may enter the body of the container and pass therefrom to the heat transfer device and after circulating through the gas passages therein it may pass out through a pipe in the wall of the container as will be presently described its exit being controlled by suitable devices to regulate the amount of pressure of the gas allowed to escape. As will be presently seen the heat of any liquid in the transfer device if constructed and located as shown and described will be instrumental in assisting the evaporation of the ice in the containers 4 which will exert a direct cooling effect upon any contents of the cooler 1 and in acquiring heat from the body to be cooled will release the CO₂ gas. CO₂ gas accumulating in the container or cooler 1 made gas pressure-proof may be withdrawn therefrom through the 75

pipe 15 communicating with the gas space within the cooler and furnished on the outside of the cooler with the proper gas shut-off indicated at 16. A construction of heat transfer device, suitable for permitting circulation of the water to be cooled and the cooling gas and having walls or plates exposed on one side to the circulating water and on the other to the circulating CO₂ gas, is as follows. The outer and inner walls 10 respectively of liquid-circulating shells or drums are indicated respectively at 17 and 17'. Any number of such drums or shells may be used although in the present instance I show four which are connected with one another by the 15 pipes 19, to allow free circulation through said drums from the liquid inlet 20 to the liquid outlet 21.

The construction shown provides spaces for free circulation of the CO₂ gas emitted from pipe 5 around said liquid shells and to the spaces with which pipe 15 connects. Obviously suitable gas-tight seals should be provided on the pipes 20, 21 and 15 where they pass through the walls of the cooler and should be constructed to prevent 25 leak under the very considerable gas pressure created on the interior of the cooler through delivery of the high pressure gas from the drums 4 through the pipe 5. The gas after delivery from pipe 5 and after circulation through the 30 interior gas-holding spaces may be delivered through outlet 15 under high pressure for carbonating or other purposes. The inlet 20 and outlet 21 are both provided with a suitable shut-off valve for convenience of operation of the 35 device. The liquid-circulating or containing member as so far described may be supported by a metal extension 22 which may be cylindrical in form and extend from the liquid container, said extension 22 being provided with the 40 brackets or elbows at the top adapted to rest at the top edge of the wall of the body 1 of the cooler which of course may be otherwise supported. The supporting extensions 22 may extend down to connection with the bottom plate 45 22' upon which the liquid cooling shells are supported or which forms the bottom of said shells. As shown additional support for the shells and the pipe connecting 20, 21 is afforded by running the pipes through the supports 22. Support 22 being in the form of a cylinder will give stiffness and added supporting capacity. Preferably 50 a space is left between it and the inner wall of the body 1 to allow circulation of CO₂ gas to the outlet pipe 15.

55 Safety valves 32 may be applied to the connections between the drums or containers and the gas feed or outlet pipe 5 leading to the cooler. In some cases it will be sufficient to apply said safety valve to the connection 5 only thus reducing the number of safety valves or said valves 60 may be applied to the ice drums themselves so as to open in case extreme pressure develops in the drum while it is not in use for supplying the cooling gas to the cooler.

65 Near the end of the outlet pipe 5 and preferably within the cooling portion of the device a valve 33 is placed in the pipe to control or adjust the flow of the gas generated in the drums and passing from said drums into the gas-holding spaces. 70 Said valve is automatically controlled by a suitable thermostat in any desired way, the casing of which is shown at 34. The action of this device is adjusted to open the valve by the thermostatic control when the temperature in the gas space to 75 which the thermostat is exposed is higher than

a predetermined degree and to close said valve when the temperature falls to a certain predetermined degree, the action being predetermined by the adjustment of the thermostat or its associated devices.

5 By this means I can control the evaporation thermostatically by the varying temperature of the chamber over the liquid, where that type is used, or the temperature in the inside chamber where the gas is used in the main chamber 10 and the liquid runs through passageways with which the gas is in contact.

A pressure reducing valve 35 may be inserted in the outlet 5 to reduce the pressure in the gas spaces of the container to the desired extent. At 15 36 is indicated a manually controlled valve in the outlet from pipe 5 into the high pressure gas spaces, the operating stem of which extends through the casing where it is provided with a handle 38. A thermometer 39 is connected by 20 a tube 40 with the interior gas spaces and is adapted to indicate the interior temperature of the cooler. In case the thermostat control should not operate properly the hand operated valve can be actuated to turn the cooling gas off and on 25 as the thermometer 39 may indicate is necessary. Instead of making the connection from pipe 5 to the outlet 36 through the automatic valve 33 it may be made as a bypass from 5 around valve 33 and as shown in Fig. 7, so that if the valve 33 30 under thermostatic control should stick or fail to open valve 36 may be manipulated under this condition or under any other condition requiring that the flux of the gas under pressure from pipe 5 into the gas spaces shall be controlled manually 35 and in a way entirely independent from the thermostatic control.

In the modification illustrated in Figs. 3 and 4 a similar construction is shown wherein the form of the invention illustrated in Fig. 1 is modified 40 to cause the CO₂ gas to circulate in the drums or shells which in Fig. 1 are occupied by the liquid. In the case of Fig. 3 the liquid to be cooled is contained in the cylinder 22 supported as before or in any other suitable manner and is circulated therethrough in contact with the walls of the shells through which the CO₂ gas flows. In this instance the outlet of pipe 5 connects directly with the spaces between the outer and inner walls 17, 17' of said shells or drums and is 50 delivered from said spaces through an outlet 23 into the space between and around the drum or cylinder 22 from which space it may be removed for carbonating or other purposes by means of the outlet pipe 15 and valve 16 as in the case of 55 Fig. 1. The inlet and outlet pipes for the circulating water indicated at 20, 21, in this instance obviously should communicate with the water spaces in the cylinder 22.

Fig. 5 shows a construction modified to restrict 60 the dimensions and permit cooling and carbonation of a body of liquid without circulation of the same. In this instance I provide concentric cylinders 24, 24' preferably of metal and forming between them a gas-retaining space.

65 Chamber 1 constitutes the outer bounding wall of the liquid-containing space holding a body of liquid 25 within the inner wall 24 which is preferably secured to or forms a continuation of a bottom 26 for the liquid container. Within the 70 liquid container are mounted the one or more ice-holding drums or supports 4 which may be sustained at their bottoms upon the bottom 26 of the liquid container by means of suitable brackets or frames 27. The bottoms of said ice contain- 75

ers are connected by pipes or passageways 28 with the space under the liquid container which space as shown also is in free communication with the space between the outer and inner walls 5 24, 24'. The tops of the ice containers or holders 4 are open freely to the space at the top of the container 1 which is closed normally by the gas pressure-proof cover 1' secured to the top of the cooler 1 in the manner already described or in 10 any other suitable way so as to secure the gas-holding spaces within the cooler against escape of the gas under the considerable pressure developed by the conversion of the ice into gas by transfer of heat thereto from the contents of the cooler.

15 The gas under pressure in the space above the water is in contact with the surface thereof and by absorption charges the water or carbonates the same. The surplus gas under pressure accumulated in the space above the water may 20 escape through the pipes or passageways 28 and be drawn off through the pipe 15 and employed for any desired purpose, its escape from the cooler being controlled by the valve 16.

Each ice container 4 may be provided as shown 25 with an ice-supporting shelf 29 for supporting a cake of CO₂ ice introduced into the container through the open top of the drum 4 after removal of the cover 1'. The water cooled and carbonated or other liquid cooled in the container 30 may be withdrawn by means of the valve 30.

This form of my invention is especially applicable for use by bottlers since the water to be carbonated is effectually cooled and carbonated by the gas in the cooler under the high pressure 35 developed or retained therein. The surplus gas not absorbed by contact with the surface of the water and accumulated under pressure can be drawn off from the space between the outer and inner walls 24, 24' by pipe 15 and valve 16 and used for any desired purpose, as for instance, for carbonating water in separate devices into which the cooled water is introduced. This forms a very effectual arrangement since as well known the colder the water the faster and better is the carbonation obtained. Also owing to the high pressure of the gas in contact with the body of water in the cooler, the water becomes partially carbonated.

Referring now to the modification of construction illustrated in Fig. 7, this figure shows the safety valves slightly changed in location but otherwise operating in the same way as the valves shown in Fig. 1. In this instance the metal drums for the ice are provided with removable caps or seals at the lower ends or ends opposite those from which the connections are taken to pipe 5. These caps or seals may be in the form of plugs screwing into the body of the metal drum from beneath like the breach block of a gun. This figure also shows how the manual control of the flow of gas into the gas space may be effected by placing a control valve in a bypass 41 around the thermostatically controlled valve 33 as already described.

65 Referring now to the modification illustrated in Fig. 8, the metal drums having the proper caps or plugs removable to allow insertion of the CO₂ ice may be provided with gas exit nipples indicated at 42, adapted to register with or screw 70 into or down upon hollow seats 43 through which the gas passes by pipes 44 to the three-way valve 8 controllable as already described by handle 12, the gas connections being in this instance entirely within the cooling chamber instead of 75 outside or over the cap or cover 1'. The drums

may be screwed down onto the seats indicated after being loaded from the top through the removable heads 9. In this instance a top plate 45 of the cooler chamber containing the gas under pressure which is delivered thereto through the valve 8 and outlet therefrom leading into said chamber may constitute a support for the drums and the piping and valves used in connection therewith. If desired the gages instead of being mounted on the heads or caps for receiving gas pressure therethrough may be connected to the pipes leading from the seats 43 to the control valve 8 as shown.

In Fig. 9 I show how the CO₂ gas released from CO₂ ice shipped in a suitable container and accumulated under high pressure in said container may be utilized at any desired lower pressure. In this case 1 typifies a shipping container or car for solid CO₂ shipped in large quantities. Said container 1 as before described is so constructed 20 as to withstand high internal pressures and to effectively collect and retain the CO₂ gas released from the ice during transit at which time it necessarily gasifies to a greater or less extent. Said container is provided with a suitable outlet leading to pipe 50 furnished with a safety valve 51 and preferably with a pressure gage 52. In the connection from pipe 50 to a gasometer or gas collector 54 is inserted a suitable pressure reducer 53 adapted to reduce the gas pressure to any desired amount in tank or gasometer 54. A low pressure gas collected and stored in tank 54 may be withdrawn if desired for any desired purpose. After arrival of the car or container 1 at its destination or after the ice has been installed therein for a suitable length of time the accumulated gas may be withdrawn into the gasometer or storage tank 54 and the ice of necessarily reduced bulk may be afterwards removed from container 1 for any desired use. Suitable couplings in the 35 piping or connection 50 from the container 1 can be provided for use at the time of recovering the accumulated gas in the tank 1.

The utility of my invention is not limited to any particular gas nor to any particular degree of pressure of gas within the container and while in parts of the specification and claims I have used the expression "high pressure" it is to be understood that as a means for refrigerating the contents of the cooler by the action of CO₂ ice and the gas evolved therefrom, the invention is of use no matter what degree of gas may be present within the cooler. As will be seen by the use of my invention the re-loading of the cooler with the refrigerant ice is greatly facilitated since the ice is retained in a holder or container which of itself is adapted to withstand heavy pressures and it may be conveniently re-loaded with the ice from the outside of the cooler without dismantling the cooler or allowing the gas to escape from within 55 the same.

What I claim is:

1. In a cooling apparatus employing ice adapted to release gas as a cooling agent the combination with a cooler having confined spaces adapted to withstand high internal pressures of gas released from the ice and accumulated therein, a steel tank or drum having a removable head and adapted to withstand the heavy pressures generated when loaded with carbon dioxide ice, means for supporting said drum in said cooler in position to be heated by the contents of the cooler and with the removable head located outside the top of the cooler, a delivery passageway whereby the accumulated gas may be delivered therefrom and 75

means for opening or shutting off said passageway at will as for the purpose described.

2. In an apparatus for cooling and charging liquids by the use of ice adapted to release gas in the cooling operation, the combination of a steel drum or tank having a removable head and adapted to receive a load of the ice, means for supporting said drum in vertical position with the body thereof within the cooling chamber and 10 with the head on the outside to facilitate loading, a pipe or passageway conducting the gas evolved in the drum downwardly into the free space of the cooler, a liquid holder the walls of which form a wall of a passage for said gas, a cooling chamber 15 forming also a gas collecting and retaining chamber and being hermetically sealed and pressure proof so as to accumulate a gas pressure of the desired amount and means for delivering said gas under such accumulated pressure directly through 20 a suitable outlet.

3. In an apparatus for cooling and carbonating liquids the combination with a sealed pressure proof cooling chamber, a sealed drum or cartridge for ice capable of evolving gas and removably 25 supported in position with the walls of the cartridge exposed to heat transfer of the contents of the cooler and a conductor leading from the gas space of said cartridge to the gas collecting space within the cooler chamber and means for 30 circulating liquid and gas in heat transfer relation within said gas collecting space.

4. In a cooling device employing a material adapted to release gas as the refrigerant, a closed cooling chamber provided with a hermetically 35 sealed pressure-proof gas holding space therein combined with means for supporting in said chamber a sealed metallic container for the ice or other cooling material adapted to release gas by transfer of heat from the contents of the chamber, the gas pressure space of the container being in connection with the gas pressure space of the chamber and means for circulating liquid and gas through said gas pressure space in heat transfer relation, the gas circulating portion being 40 in connection with said gas pressure space and with a suitable valve controlled outlet.

5. In a cooling device employing ice consisting of a gas reduced to solid or ice form as the refrigerant, a closed cooling chamber provided with 50 hermetically sealed pressure-proof gas holding spaces combined with means for supporting therein a sealed container for the ice or other cooling material adapted to release gas by transfer of heat from the contents of the cooler, a 55 valve controlling the passage of the gas from said container to said gas holding space, a holder of liquid in said gas holding space provided with means for circulating the liquid therethrough and means for circulating the gas through a heat 60 transfer device a wall of which is common to the liquid holder and the passageway for the gas.

6. In an apparatus employing as the refrigerant an ice adapted to release a gas in the cooling operation, a cooling container hermetically sealed 65 and adapted to hold gas under high pressure said container providing a gas circulating space, means for supporting a sealed container of the ice therein in position to utilize the heat from the contents to be cooled for evaporating the ice, 70 said sealed container being connected with the gas space of the cooler and means for controlling the passage of the gas from the ice container to the gas circulating space for the cooling gas in the cooler said means embodying a valve having 75 a valve stem extending through a wall of the con-

tainer and means for withdrawing gas under pressure from the gas space of the cooler for charging a liquid or other uses.

7. A cooling device employing CO₂ ice as the cooling agent and having a sealed pressure-proof 5 gas retaining space or compartment in combination with a multiplicity of ice containers or receptacles having gas spaces connected with the gas retaining space and means for controlling the connection of said containers with said gas space 10 to permit them to be put into service and withdrawn from service at will.

8. In an apparatus for cooling by the use of ice adapted to release a cooling gas when it absorbs heat from the contents of the cooler, the 15 combination with a hermetically sealed pressure retaining cooling chamber having gas circulating spaces therein of a sealed pressure retaining drum or cartridge for the ice supported within said chamber and having a removable head accessible 20 to permit the drum to be re-loaded with ice from the outside of the cooler in combination with means for controlling the passage of accumulated gas from said drum to the gas circulating spaces through which the cooling gas circulates. 25

9. A cooling device employing CO₂ as the cooling agent comprising a sealed gas containing chamber, means therein for conducting a liquid to be cooled through said chamber, a sealed pressure-retaining drum for the CO₂ ice supported 30 within said chamber with said drum spaced from said liquid and the conducting means therefor, means connected to said drum for conducting gas from said drum to said chamber and means for withdrawing only the utilized gas from 35 said chamber which has passed said liquid conducting means.

10. A cooling device employing CO₂ as the cooling agent comprising a sealed gas containing chamber, means therein for conducting a liquid 40 to be cooled through said chamber, means for supporting a body of CO₂ ice within said chamber with said ice spaced from said liquid and the conducting means thereof, the gases from said CO₂ ice passing downwardly into contact with 45 said liquid conducting means and means for withdrawing only the gases which have passed said liquid conducting means.

11. In a cooling apparatus, a gas receiving space, means for conducting liquid therethrough, 50 means for supporting a body of CO₂ ice in the upper portion of said gas receiving space in position to supply gas to said space, said gas receiving space including a gas conducting passage passing downwardly and upwardly along different 55 portions of said liquid conducting means from said body of ice to an outlet for CO₂ gas from said space.

12. In an apparatus for cooling by ice adapted to evaporate as a gas when it absorbs heat, a 60 pressure retaining hermetically sealed cooling chamber having gas circulating cooling spaces and having a hermetically sealed pressure retaining container for the ice projecting into the cooling chamber through the top wall thereof but 65 having a removable head or cap located outside said wall to facilitate reloading without disturbing the gas connections of said ice container within the chamber, a valve controlled passageway for the gas evolved leading from the gas space in 70 said sealed ice container into the gas circulating cooling spaces of the chamber and means for conducting said gas from said cooling chamber out through a wall thereof.

HARRY S. CORNISH.
